(57) **CLAIM**

The ornamental design for an athletic timing device, as shown and described.

DESCRIPTION

FIG. 1 is a left perspective view from the front and above of an athletic timing device showing the new design.

FIG. 2 is a front view of the athletic timing device shown in FIG. 1.

FIG. 3 is a rear view of the athletic timing device shown in FIG. 1

FIG. 4 is a top view of the athletic timing device shown in FIG. 1.

FIG. 5 is a bottom view of the athletic timing device shown in FIG. 1.

FIG. 6 is a left view of the athletic timing device shown in FIG. 1; and,

FIG. 7 is a right view of the athletic timing device shown in FIG. 1.

The broken lines shown in the figures are for the purpose of illustrating locations of display and user interface elements, and form no part of the claimed design.
